UNITED STATES PATENT OFFICE.

THOMAS H. CUMMINGS, OF ST. LOUIS, MISSOURI, ASSIGNOR OF ONE-HALF TO HATTIE L. CUMMINGS, OF ST. LOUIS, MISSOURI.

AUTOMATIC LUBRICATOR FOR GASOLINE ENGINES.

Application filed December 23, 1921. Serial No. 524,434.

To all whom it may concern:

Be it known that I, THOMAS H. CUMMINGS, a citizen of the United States, and resident of the city of St. Louis, and State 5 of Missouri, have invented certain new and useful Improvements in Automatic Lubricators for Gasoline Engines, of which the following is a specification containing a full, clear, and exact description, reference being 10 had to the accompanying drawings, forming a part hereof.

My invention relates to improvements in automatic oilers for gasoline engines, and has for its primary object an oiler in which 15 a quantity of oil can be stored, and which will automatically feed oil to the crank case as it is used.

A further object is to construct an automatic oiler which will maintain a constant 20 level with lubricating oil within the crank case of a gasoline engine.

In the drawings:

Fig. 1 is an end elevation of a gasoline engine with my device attached thereto, with 25 parts of the crank case broken away and in section;

Fig. 2 is a sectional view taken on the line 2—2, of Fig. 3 viewed in the direction of the arrow, with parts of the reservoir broken 30 away and in section; and

Fig. 3 is a sectional view taken on the line 3—3 of Fig. 2, viewing the same in the direction of the arrow.

In the construction of my device, 4 represents the crank case of a gasoline engine and 5 the drain plug. Secured to the crank case is a feed pipe 6, which is provided with a stop cock 7 so that the pipe can be shut off from the crank case.

40 The pipe 6 terminates in an auxiliary reservoir 8, which may be formed integral with or secured to the main reservoir 9 in any well known manner such as soldering and the like, in which latter case the auxiliary reservoir consists of a top, a bottom, one side and two ends, the wall of the main reservoir forming the remaining side. The wall 10 of the reservoir is provided with a plurality of openings 11, these openings being adjacent the bottom of and opening into the reservoirs 8 and 9. At a distance above the openings 11 is an opening 12, which is also formed through the wall 10 and opens into the reservoirs 8 and 9.

55 The reservoir 8 is provided on its upper

end with a stop cock 13 which when operated acts as an air vent. The reservoir 9 is provided with a gauge glass 14 so that the amount of lubricant contained in the reservoir can be readily determined. 60

The reservoir 9 is also provided with a filler neck 15 on which a screw cap 16 is secured. This is for the purpose of making the reservoir 9 air-tight as will be fully explained later. 65

It is essential in the construction of my device that the upper edge of the opening 12 be on a line with the oil level in the crank case. The reservoir 9 is secured either to the crank case or other suitable part of 70 the engine by means of a bracket 17.

The operation of my device is as follows: After the device has been secured to the engine, the stop cocks 7 and 13 are closed, the cap 16 removed and the reservoir 9 filled 75 with oil. The cap 16 is then replaced, making the reservoir 9 air-tight. The stop cock 7 is opened, and then the stop cock 13. The opening of the stop cock 13 permits air to pass into the auxiliary reservoir 8, then 80 through the opening 12, where it rises through the oil while the oil contained in the reservoir 9 flows into the reservoir 8 through the openings 11, and from there through the pipe 6 into the crank case 4. 85

When the oil in the crank case has risen to a height equal to the upper edge of the opening 12, the reservoir 8 will also be filled to that point. This seals the air vent 12 and prevents any more air from entering the 90 reservoir 9, thus stopping the flow of oil from the reservoir 9 into the auxiliary reservoir 8.

When the oil level in the crank case 4 has dropped and lowered the oil level in the auxiliary reservoir sufficiently to uncover the opening 12, air will again be admitted to the reservoir 9 and permit oil to flow into the auxiliary reservoir.

By the use of my device it is possible to 100 always carry a large reserve of lubricant for the crank case, and the motorist is not dependent upon oil stations along the road to keep the proper supply of lubricant within the case.

105 My device can be readily attached to any one of the oil level cocks now present in the crank case of an automobile engine, and eliminates the necessity of testing the crank case to ascertain whether a sufficient amount 110

of oil is contained therein, as it is only necessary to raise the hood to view the sight glass 14 to ascertain the contents of the reservoir 9. If this reservoir contains oil it is an assured fact that there is sufficient oil in the crank case.

Having fully described my invention, what I claim is:

1. An automatic lubricator for gasoline engines comprising a main reservoir provided with an air tight closure on its top for the introduction of lubricant, oil passages formed in one wall thereof adjacent its bottom, an air passage formed in said 10 wall adjacent to and above said first mentioned passages, an auxiliary reservoir formed integral with the main reservoir, said auxiliary reservoir enclosing said openings and having its bottom in the same 15 plane as the bottom of the main reservoir, a stop cock for admitting air to the auxiliary reservoir, a stop cock secured to the bottom of said auxiliary reservoir, a pipe secured to the last mentioned stop cock and to the 20 crank case of a gasoline engine, and a bracket for securing the main reservoir to the crank case of said engine.

2. An automatic lubricator for gasoline engines comprising a main reservoir provided on its top with an air tight closure for

the introduction of lubricant, oil passages formed in one wall thereof adjacent its bottom, an air passage formed in said wall adjacent to and above said first mentioned passages, an auxiliary reservoir having a top, a bottom, two end and one side walls secured to said main reservoir, said auxiliary reservoir enclosing all of said openings and having its bottom in the same plane as the bottom 35 of the main reservoir, the wall of the main reservoir to which the auxiliary reservoir is attached serving as the sixth side thereof, a stop cock for admitting air to the auxiliary reservoir, secured to the top thereof, a pipe secured to the auxiliary reservoir at its bottom and communicating with the crank case at a point below the mean oil level to be maintained therein, a stop cock located between the auxiliary reservoir and crank case 40 for shutting off the flow of oil thereto, and a bracket for securing the main reservoir to the crank case of a gasoline engine in such a position that when the mean oil level in the crank case is attained, the air vent will be closed off by the lubricant in the auxiliary reservoir.

In testimony whereof, I have signed my name to this specification.

THOMAS H. CUMMINGS.
